HAMILTON ERASTUS SMITH, OF NEW YORK, N. Y., ASSIGNOR TO MARY JANE SMITH, OF SAME PLACE.

Letters Patent No. 96,361, dated November 2, 1869; anteuated October 22, 1869.

IMPROVED CLOTHES-MANGLE.

The Schedule referred to in these Letters Patent and making part of the same.

To all whom it may concern:

Be it known that I, HAMILTON ERASTUS SMITH, of New York, in the county of New York, and State of New York, have invented a new and improved Clothes-Mangle; and I do hereby declare that the following is a full, clear, and exact description thereof, which will enable others skilled in the art to make and use the same, reference being had to the accompanying drawings, forming part of this specification, in which—

Figure 1 represents a front elevation, partly in section, of my improved clothes-mangle.

Figure 2 is a vertical transverse section of the same, taken on the plane of the line $x x$, fig. 1.

Figure 3 is a detail vertical transverse section, taken on the plane of the line $y y$, fig. 1.

Similar letters of reference indicate corresponding parts.

This invention relates to a new clothes-mangle, which has for its object to provide secure bearings for the roller, upon which the clothes to be smoothened are wound, and which carries two or more pressure-rollers, between which the clothes are pressed.

The invention consists of an apparatus of such construction, that on a stationary frame, and on another pivoted frame, indented lugs are formed, in which the roller carrying the clothes has its bearings when the pivoted frame is swung down toward the stationary frame. The said roller has therefore a secure bearing, and can, at any time, be taken off by raising the pivoted frame. The two frames both carry rollers, between which the articles on the removable roller are pressed.

A, in the drawing, represents the stationary frame of the mangle, it being supported on suitable lugs, B, and provided with a horizontal plate, a .

A horizontal roller, c , has its bearings in boxes provided in the ends of the frame A.

D is a frame, which consists, chiefly, of two side-bars, d , which are, by a connecting-bar, e in front connected with a treadle, E, that is pivoted to the rear of the frame A, as shown in fig. 2, while their rear ends are, by pins f , pivoted to lugs g , that project from the frame A.

F is a roller, which has its bearings in boxes G, that are fitted into recesses of the side-bars d , so that they can slide up and down therein.

A spring j is interposed between the top of each box G, and the upper end of a hollow arm, i , projecting from each bar d , as is clearly shown in fig. 3.

The treadle E can, by a suitable spring-catch I, be locked in any desired position, as indicated in fig. 1.

To the inner sides of the bars d are fastened downward-projecting plates l , which have hook-shaped lower edges, as shown in fig. 3, and opposite to them are, on the frame A, upward-projecting plates, m , which are also hook-shaped, but in a direction opposite to that of the plates l , so that when the two sets of plates l m are brought together, by depressing the frame D, nearly circular openings are formed between them, into which the projecting ends of the axle n of a roller J can be fitted.

This roller J is to receive the articles that are to be smoothened, and is, for that purpose, removed from the machine. When to be inserted between the rollers C F, the frame D is raised, and the axle n placed upon the plate m , then the frame D is lowered and locked, and the axle n will be securely held in its bearings.

By applying rotary motion to one of the rollers C, F, or J, either by means of a crank, o , or otherwise, all the rollers will be turned, and the clothes on the roller J will be smoothened. The roller J is, by this arrangement, firmly held, and cannot play laterally, while it is up and down adjustable to greater or less pressure.

Having thus described my invention,

I claim as new, and desire to secure by Letters Patent—

The plates l , on the swinging frame D, in combination with the plates m , on the stationary frame A, when arranged to support and hold the ends of the roller J, upon which the articles to be rolled are wound, as specified.

HAMILTON E. SMITH.
